COVER AND LOCKING DEVICE FOR
CONTAINERSFred Susie and Harvey Reingardt, Marshalltown,
Iowa

Application June 8, 1933, Serial No. 674,830

2 Claims. (Cl. 217—94)

The present invention relates to a cover or closure construction, and more in particular to a novel locking mechanism for locking the cover or closure on a container.

5 Among the objects of the present invention is to provide a novel construction of detachable cover or closure for a container which is adapted to be readily assembled, removed or replaced with a minimum amount of effort, and which at all times forms a tight closure or seal for the container. The present invention, although primarily adapted for use on containers holding perishable products, food or other material, is admirably adapted for use wherever a detachable and tight closure is desired or essential.

10 15 A further object of the present invention is to provide a novel construction of locking device for a cover or closure for a container, permitting the cover to be readily removed or replaced for inspection or removal of the contents, without in any way injuring the cover or its means for connecting it to the container.

20 25 A still further object is to provide a novel means and method of connecting a cover or closure to a container such as a tub, barrel or the like, such means permitting ready removal and replacement of the cover or closure.

30 35 Another object of the invention is in the provision of a novel means for locking a cover or closure on a container and including a wire band or hoop adapted to encompass the container and provided with a lever connected to the ends of the wire band or hoop in such a manner as to lengthen or shorten the effective length thereof, whereby to release or lock the cover or closure in position.

40 45 Further objects are to provide a construction of maximum simplicity, efficiency, economy and ease of assembly and operation, and such further objects, advantages and capabilities as will later more fully appear, and as are inherently possessed thereby.

50 The invention further resides in the combination, construction, and arrangements of parts illustrated in the accompanying drawing, and while there is shown therein a preferred embodiment, it is to be understood that the same is susceptible of modification and change, and comprehends other arrangements and details, without departing from the spirit of the invention.

In the drawing:

Fig. 1 is a view in perspective of a container provided with the novel closure construction.

Fig. 2 is a fragmentary view in side elevation showing the position of the wire hoop and of the

lever which is connected thereto, when the lever has been released to permit removal of the cover.

Fig. 3 is a view similar to Fig. 2, but disclosing the position of the wire hoop and the lever in locked or latched position.

Fig. 4 is a fragmentary view in perspective of one of the connecting links attached to the band or annular ring around the cover or closure.

Fig. 5 is a fragmentary view in vertical cross section taken in a plane represented by the line 10 5—5 of Fig. 1.

Fig. 6 is a fragmentary view in vertical cross section taken in a plane represented by the line 6—6 of Fig. 1, but including means for sealing the lock or latching means.

Referring more particularly to the disclosure in the drawing, the reference character 1 designates generally a container such as a tub, barrel or the like. This container is shown as constructed of wood, although it is to be understood that the same may be made of cardboard, metal or other material suitable for the purpose. Encompassing this container are provided spaced hoops or wire bands 2. A cover or closure 3 is adapted to seat upon and close the upper end of the container, and is provided with a depending band or annular ring 4 adapted to encompass or encircle the upper and outer edge of the container.

20 25 30 35 The band or annular ring 4 has a series of clips 5 suitably connected thereto as by welding or the like. These clips are shown as doubled over and provided at their lower ends with an opening adapted to receive a hoop 6. This hoop is open and the ends 7 and 8 thereof are pivotally connected to a lever or arm 9. This arm or lever is provided at its outer end with a rearwardly and outwardly bent flange or finger 10 adapted to be received in an off-set portion 11 formed in the hoop 6.

40 45 50 As disclosed in Fig. 3, the end or flange 10 is adapted to seat within this off-set portion and lock the hoop against the sides of the container by reason of the fact that when the lever or arm 9 is in the position shown in Fig. 3, the effective or operative length of the hoop is reduced, whereby the hoop is clamped against the sides of the tub and maintains or locks the cover in position.

When the lever is raised or unlatched as shown in Fig. 2, the effective or operative length of the hoop is increased, and it is released from its clamping engagement with the sides of the container. Thus the arm or lever is so arranged as to vary the operative length of the hoop whereby when the arm is moved in one direction, the length of the hoop is reduced and its clamping engage- 55

ment with the sides of the container anchors the cover in position, and when the arm or lever is moved in the other direction, the effective length of the hoop is increased and the cover may be 5 readily and easily removed or replaced, as the occasion may require. Each strip 5 is provided with a rearwardly extending point or projection a which is suitably formed thereon, or pressed out from the body thereof. This point or projection 10 is pressed or forced into and embeds itself in the sides of the container when the operative length of the hoop 6 is reduced by throwing the lever or arm into its locking or latching engagement, and by reason of the connection of the hoop 15 with the turned over portions of the clip 5, the points a are withdrawn from embedding engagement with the sides of the container when the lever is thrown to unlocking position. These points or projections prevent the cover from being 20 accidentally displaced or removed.

In order that the cover and hoop which is adapted to be clamped onto the container may fit containers even though they vary slightly in their diameter, this wire hoop is provided with 25 off-sets or kinks 12 to permit an elongation of this wire. These kinks are particularly advantageous when the cover is employed on wooden containers which are normally water soaked before being filled or packed and thus vary in their diameters, 30 although it frequently happens that even in cardboard, metal or other containers, there is a slight variation in size or diameter.

It is often desirable that containers, especially 35 those containing food stuffs or perishable products, be sealed after they have been inspected. In order to permit such sealing so as to prevent tampering with the contents thereof, the lever or arm is provided with an opening 13 to permit the insertion of a wire or seal 14 which may be 40 passed therethrough and around the hoop 6 as shown in Fig. 6.

The present construction permits an elimination 45 of the upper hoop of the barrel since the open hoop which is connected to the cover or closure will take its place. However, if the container is already supplied with such a hoop, the present construction does not necessitate its removal.

From the above description and the disclosure in the drawing, it will be readily apparent that the invention comprehends a novel construction of cover or closure for a container, which cover or closure is adapted to be readily assembled, removed or replaced, and when assembled, is latched or locked against accidental removal or displacement.

Having thus disclosed the invention, we claim:

1. A closure for a container or the like comprising 10 a cover adapted to seat on the open end of said container, a band depending from said cover, clips depending from said band, an open hoop adapted to encompass the container and carried by said clips, a lever connected to the ends of said hoop for varying the operative length thereof whereby to clamp said hoop and clips to the container to lock the cover in position or to release it therefrom for ready removal or replacement of the cover, and projecting means carried by said clips adapted to be forced against or into the sides 15 of the container by the hoop whenever the length of the hoop is decreased to clamp it on the container.

2. A closure for a container or the like comprising 20 a cover adapted to seat on the open end of the container, a band depending from said cover, clips depending from said band, each clip having a projection on its inner face, an open hoop adapted to encompass the container, said clips having turned over portions for fixedly engaging said hoop, and a lever connected to the ends of said hoop for varying the operative length thereof, whereby to clamp said hoop and clips to the container to lock the cover in position or to release it therefrom for ready removal or replacement of the cover, the projections carried by said clips 25 being adapted to be forced into or against the sides of the container by the hoop whenever the length of the hoop is decreased to clamp it on the container and adapted to be pulled away from the sides of the container by the hoop whenever the length of the hoop is increased.

FRED SUSIE:
HARVEY REINGARDT.
